United States Patent [19]
Mendenhall

[11] **Patent Number:** **Des. 290,462**
[45] **Date of Patent:** **** Jun. 23, 1987**

[54] **EXHAUST GAS RECIRCULATION VALVE COVER**

4,347,822 9/1982 Casey 123/445
4,508,134 4/1985 Kelly et al. ..... 123/568 X

[75] **Inventor:** **Charles A. Mendenhall, Rochester, N.Y.**

Primary Examiner—B. J. Bullock
Assistant Examiner—Brian N. Vinson
Attorney, Agent, or Firm—C. K. Veenstra

[73] **Assignee:** **General Motors Corporation, Detroit, Mich.**

[57] **CLAIM**

[**] **Term:** **14 Years**

The ornamental design for an exhaust gas recirculation valve cover, as shown and described.

[21] **Appl. No.:** **645,237**

DESCRIPTION

[22] **Filed:** **Aug. 29, 1984**

FIG. 1 is a top plan view of an exhaust gas recirculation valve cover showing my new design;

[52] **U.S. Cl.** **D15/5**

FIG. 2 is a front elevational view thereof;

[58] **Field of Search** **D15/5; D12/155, 197;**

FIG. 3 is a left side elevational view thereof;

123/434, 568-571; D9/300, 448

FIG. 4 is a right side elevational view thereof;

D13/1

FIG. 5 is a rear elevational view thereof;

D13/1

FIG. 6 is a top perspective view thereof;

D13/1

FIG. 7 is a top plan view of a second embodiment thereof;

D13/1

FIG. 8 is a front elevational view of FIG. 7;

D13/1

FIG. 9 is a left side elevational view of FIG. 7;

D13/1

FIG. 10 is a right side elevational view of FIG. 7;

D13/1

FIG. 11 is a rear elevational view of FIG. 7; and

D13/1

FIG. 12 is a top perspective view of FIG. 7.
